UNITED STATES PATENT OFFICE.

HENRY EVERSON, OF HEMPSTEAD, NEW YORK.

FOLDING COOP OR KENNEL.

SPECIFICATION forming part of Letters Patent No. 294,600, dated March 4, 1884.

Application filed December 13, 1883. (Model.)

To all whom it may concern:

Be it known that I, HENRY EVERSON, of Hempstead, in the county of Queens and State of New York, have invented certain new and useful Improvements in Folding Coops or Kennels; and I do hereby declare the following to be a full, clear, and exact description of the invention, such as will enable others skilled in the art to which it pertains to make and to use it, reference being had to the accompanying drawings, which form part of this specification.

My invention relates to an improvement in folding coops or kennels; and it consists in the combination of the bottom piece provided with rigid side strips, the folding sides, the hinged end piece, which folds down upon the bottom, in between the rigid side pieces, an end piece or pieces, and the hinged roof, as will be more fully described hereinafter.

The object of my invention is to produce a folding coop or kennel which, when no longer needed, can be folded up and stored away in a very small space, and which can be transported more cheaply than coops of the same size which are constructed in the usual manner.

Figure 1 is a perspective of my coop ready for use. Fig. 2 is an end view of the same, showing the slatted end pieces removed. Fig. 3 is a perspective showing a portion of the coop folded together. Fig. 4 shows the entire coop folded together for transportation. Fig. 5 shows an end piece to be placed in front of the slatted end piece at night.

A represents the bottom piece of the coop, which is strengthened by the cleats B. Secured along opposite sides of the bottom piece, A, are the vertical rigid cleats C, to the upper edges of which the side pieces D are hinged.

These rigid pieces C are used for the purpose of raising the point at which the side pieces D are hinged to a point above where the end piece E is hinged to the bottom. The end piece E, which forms a permanent part of the coop, in contradistinction to the opposite removable end, is hinged to the rigid cross-piece E', which is secured upon the top of that end of the bottom. This end piece is just wide enough to fit snugly between the side cleats C when it is folded down upon

the top of the bottom A. As the cross-piece E' raises the lower end of the piece E above the bottom when the end is folded inward upon the bottom, it does not rest solidly upon the bottom, but extends horizontally above it just far enough to allow the end piece H to be placed under it. The side cleats C raise the side pieces D just high enough to allow them to close solidly down upon the end piece E after it is closed. These side pieces D, being only half the width of the coop, just meet at the center and form an even solid package when all of the parts are folded together. Each one of these side pieces D is strengthened by the vertical cleats J, so as to prevent them from warping or splitting.

The roof K is formed upon each side of a number of pieces, which are secured rigidly together by means of the cleats L, which are secured to their inner sides, and which extend from one end of the roof to the other. The two sides of the roof are hinged together at their upper inner edges, and when folded together can be placed upon the other parts of the coop, as shown in Fig. 4.

In order to allow the poultry fresh air, the end F of the coop is made open, as shown in Fig. 1. This end piece will not be hinged to the bottom A, but will be made to lift in and out of the sides. In order to keep the lower ends of the end piece F in place, a block or stop, S, is secured upon the top of the end of the bottom, as shown in Figs. 3 and 4. When the coop is to be closed at night, so as to keep out rats and snakes, the end piece H' will be placed in front of the piece F, so as to close it at all points except its top, where open space is left for the purpose of allowing ventilation.

To fold the coop, the top is first removed, the end piece H placed upon the bottom, and then the end E is folded solidly down upon it. These two parts fill the space between the side cleats C. The sides D are then folded inward, as shown in Fig. 3, and the end piece H' is placed upon their tops between the cleats J. The folded top K is then placed upon the top of all the other parts.

As shown in Fig. 4, when the coop is folded together, it makes a solid and compact bundle, which occupies but little space, and which

can be transported from place to place much more readily than an ordinary coop.

Having thus described my invention, I claim—

5. A folding coop or kennel composed of the combination of the bottom piece, A, provided with rigid side strips C, the folding sides D, the hinged piece E, which folds down upon the bottom, in between the rigid side pieces

C, an end piece or pieces, and the hinged roof to K, substantially as shown and described.

In testimony whereof I affix my signature in presence of two witnesses.

HENRY EVESSEN.
